UNITED STATES PATENT OFFICE.

TIMOTHY B. POWERS, OF BROOKLYN, NEW YORK.

WATCH AND COMPASS HOLDER FOR BELTS.

Application filed May 25, 1922. Serial No. 563,604.

To all whom it may concern:

Be it known that I, TIMOTHY B. POWERS, a citizen of the United States, and a resident of Brooklyn, in the county of Kings and State of New York, have invented certain new and useful Improvements in Watch and Compass Holders for Belts, of which the following is a specification.

This invention has for its object to provide means for securing a watch or other similar article on the belt or other piece of wearing apparel, wherein the device will be extremely simple in its construction and of low manufacturing costs; and will also be secure in its attachment to the belt.

A further object of the invention is to provide such a device that can also operate as a holder for a desk watch.

In the accompanying drawing showing embodiments of my invention, Fig. 1 shows the device secured to a belt and containing a watch.

Fig. 2 is a similar view in the open position.

Fig. 3 is a vertical section through the device.

Fig. 4 shows the spring wire bail detached.

Fig. 5 shows the device in use as a desk watch holder.

Fig. 6 is a rear elevation.

Fig. 7 is a partial plan view at the end for mounting the bail.

Fig. 8 shows the elastic band and its attachment.

Fig. 9 shows a similar device used to carry a compass.

The device comprises practically but three members, one of these being a base, the second member is the wire bail that is hinged to the base by simply having bent portions project into the journal portions of the base without any additional members. And the third member is the means for retaining the watch or other article in the base, shown as a web or strip of elastic, that may have a clamping strip at each end to facilitate its attachment and removal and also renewal when desired.

The base member obviously can be used to hold other articles, and may constitute the casing of a compass of any desired construction.

As shown in the drawings, and previously set forth the main novel features are the wire bail, and its attaching means on the

base, and these are so organized and constructed that the bail being formed of a spring wire of considerable strength and resiliency, will function to hold the bail down in the plane of the base in its normal position, so that upon the bail being attached to a belt, or pocket, or other part of the wearing apparel, such as the top edge of the trousers, the watch will be normally held in the vertical position, similar to being in the watch pocket of the trousers or other garment.

The base 2 is shown as annular, and is preferably of a size to receive the crystal portion of a watch 3, exposed at the opening through the base and engaging the base by the marginal portion of the watch beyond the crystal edge. Any desired or suitable means can be provided for retaining the watch in such position, as indicated in the drawing.

The bail member is shown separately in Fig. 4, and comprises a substantially U-shaped portion with side arms 4 and 5, slightly diverging and the end portions of these arms are doubled back to form loops 6 and 7 separated a short distance to engage the opposite faces of the belt or other article, which loops extend transverse to the plane of the U portion. The extremities of the portions 6 and 7 are bent abruptly inward, as at 8 and 9, to extend toward each other, see Fig. 4, and are designed to enter journal portions on the base.

The base 2 is provided with journal portions, such as projections 10 and 11, that are provided with bores 12 and 13, extending toward each other approximately in the plane of the base; which apertured projections form journals to receive the bent extremities 8 and 9 of the bail, see Figs. 2, 6 and 7.

If these journal portions or apertures were in alignment the bail would swing freely from a position parallel and adjacent to the base, up to a position transverse thereto and even beyond, without resistance, and such bail being secured to the belt, the base or watch support would tend to swing downwardly and remain in such position, and not be held upright against the belt. But by the particular arrangement of these apertures, and the mode of bending the extremities of the bail, the base tends to swing inwardly against the belt in the upright position, and be retained in such position

by the natural resiliency of the bail. This is accomplished by the arrangement of these bores, and it will be seen from Fig. 7 which is a plan view looking downwardly on the base, that the bores are substantially parallel with a vertical plane that would pass through the axis of the bores; by looking at the base from the rear, it will be seen, see Fig. 6, that these bores are inclined 5 slightly upward, each toward the other. From this arrangement it will be understood that with the bail in the closed position against the watch, the end portions of the bail arms extending into the bores are 10 turned or twisted upwardly whereby a kind of torsion twist is applied to the loop portions 6 and 7, that results in the bail being swung downwardly against the base, so that the base with the watch is pressed against 15 the belt that passes through the loops, see Fig. 3. But it will be further seen that if the device is swung to draw the bail through a half circle, the reverse strain is applied to the bail ends. From this it follows that 20 when the bail is held transverse to the base it is on a kind of dead center on these spring ends tending to hold the watch in the horizontal position relative to the belt so that it is in a convenient position for 25 inspection by the wearer, see Fig. 2.

To prevent swinging the watch down beyond this horizontal position, the casing may be slightly extended at 14 that will engage the belt and limit the movement, as 30 shown in Fig. 3.

To secure the watch in the annular frame or base 2, various means may be employed, and as shown I provide a strip of elastic 16 having its end suitably secured on opposite 40 sides of the base that are preferably made parallel. In Fig. 8 I show a pair of channel strips 17 in which the edge of the web 16 may be inserted, with one margin 18 closed on the web. These channels on each end of the strip may engage the opposite edges of the casing to removably secure the strip.

As stated, the base can be swung to a position perpendicular to the belt and will be retained in this position, as indicated in 50 Fig. 2, but on removal of the device from the belt, and swinging it to this position, the bail will form on its portion or support, so that a desk watch holder is provided as indicated in Fig. 5.

It is to be further understood that the bail and loops can only be applied to the belt or trousers in the open position of the bail and holder as in Fig. 2, and that when the watch is swung up against the belt in the closed 60 position, as in Figs. 1 to 3, the extension 14 projecting against the lower edge of the belt, absolutely prevents removal of the bail from the belt. This is a safeguard against accidental loosening of the device or its unauthorized removal.

In Fig. 9 I show a similar construction with a modified form of base 20, the bail 21 being mounted on the base in the same manner as that shown in the other views. This base is in the form of a casing and constitutes a compass. Such device will be carried in the same manner as the watch and can be swung down for inspection when desired.

What I claim is:

1. A device of the character set forth, the combination of an annular frame, a pair of journal members at remote portions on the frame, in which the apertures extend toward each other, said apertures lying in the same plane perpendicular to the base plane, and a holder member in the form of a bail member of spring wire in which the end portions are bent backwardly parallel to form a loop on each side with the extremities bent inwardly each toward the other, said extremities being located in said journal portions under spring tension of the bail member, whereby the bail member will be normally yieldably retained in the plane of the base with the loop members above the same to form a holder for belt attachment, and means on the base for removably holding a watch or similar article.

2. A device of the character set forth, the combination of an annular frame, a pair of journal members at remote portions on the frame, in which the apertures extend toward each other, said apertures lying in the same plane perpendicular to the base plane, and a holder member in the form of a bail member of spring wire in which the end portions are bent backwardly parallel to form a loop on each side with the extremities bent inwardly each toward the other, said extremities being located in said journal portions, whereby the bail member will be normally retained in the plane of the base with the loop members above the same to form a holder for belt attachment, 100 said journal portions projecting across the loop portions in the normally parallel position of the bail to close the loops when engaging the belt, but which base member when the bail and loops are perpendicular to the base will extend beyond the loop members to permit entrance of the belt, and means on the base for removably holding a watch or similar article.

3. A device of the character set forth, the combination of an annular frame, a pair of journal members at remote portions on the frame, in which the apertures extend toward each other, said apertures lying in the same plane perpendicular to the base plane and which apertures are each slightly inclined to the base plane, and a holder member in the form of a bail member of spring wire in which the end portions are bent backwardly parallel to form a loop 125 130

on each side with the extremities bent inwardly each toward the other, said extremities being located in said journal portions, whereby the bail member will be normally retained in the plane of the base with the loop members above the same to form a holder for belt attachment, and means on the base for removably holding a watch or similar article, comprising a strip of elastic 10 removably secured on opposite sides of the base.

4. A device of the character set forth, the combination of an annular frame, a pair of journal members at remote portions on the frame, in which the apertures extend toward each other, said apertures lying in the same plane perpendicular to the base plane and which apertures are each slightly inclined to the base plane, and a holder member in the form of a bail member of spring wire in which the end portions are bent backwardly parallel to form a loop on each side with the extremities bent inwardly each toward the other, said extremities being located in said journal portions, whereby the bail member will be normally retained in the plane of the base with the loop members above the same to form a holder for belt attachment, said journal 20 portions projecting across the loop portions in the normally parallel portion of the bail to close the loops when engaging the belt, but which base member when the bail and loops are perpendicular to the base will extend beyond the loop members to permit entrance of the belt.

5. A device of the character set forth, the combination of a frame, a pair of journal members at remote portions on the frame, in which the apertures extend toward each other, said apertures lying in the same plane perpendicular to the base plane and which apertures are each slightly inclined to the base plane, and a holder member in the form of a bail member of spring wire in which the end portions are bent backwardly parallel to form a loop on each side with the extremities bent inwardly each toward the other, said extremities being located in said journal portions, whereby the bail member will be normally retained in the plane of the base with the loop members above the same to form a holder for belt attachment, comprising a strip of elastic removably secured on opposite sides of the base.

6. A device of the character set forth, the combination of a frame, a pair of journal members at remote portions on the frame, in which the apertures extend toward each other, said apertures lying in the same plane perpendicular to the base plane and which apertures are each slightly inclined to the base plane, and a holder member in the form of a bail member of spring wire in which the end portions are bent backwardly parallel to form a loop on each side with the extremities bent inwardly each toward the other, said extremities being located in said journal portions, whereby the bail member will be normally retained in the plane of the base with the loop members above the same to form a holder for belt attachment.

7. A device of the character set forth, the combination of a frame, a pair of journal members at remote portions on the frame, in which the apertures extend toward each other, said apertures lying in

the same plane perpendicular to the base plane and which apertures are each slightly inclined to the base plane, and a holder member in the form of a bail member of spring wire in which the end portions are bent backwardly parallel to form a loop on each side with the extremities bent inwardly each toward the other, said extremities being located in said journal portions, whereby the bail member will be normally retained in the plane of the base with the loop members above the same to form a holder for belt attachment, said journal portions projecting across the loop portions in the normally parallel position of the bail to close the loops when engaging the belt, but which base member when the bail and loops are perpendicular to the base will extend beyond the loop members to permit entrance of the belt.

8. A device of the character set forth, the combination of a frame, a pair of journal members at remote portions on the frame, in which the apertures extend toward each other, said apertures lying in the same plane perpendicular to the base plane and which apertures are each slightly inclined to the base plane, and a holder member in the form of a bail member of spring wire in which the end portions are bent backwardly parallel to form a loop on each side with the extremities bent inwardly each toward the other, said extremities being located in said journal portions, whereby the bail member will be normally retained in the plane of the base with the loop members above the same to form a holder for belt attachment, comprising a strip of elastic removably secured on opposite sides of the base.

9. A device of the character set forth, the combination of a frame, a pair of journal members at remote portions on the frame, in which the apertures extend toward each other, said apertures lying in the same plane perpendicular to the base plane and which apertures are each slightly inclined to the base plane, and a holder member in the form of a bail member of a single piece of spring wire in which the end portions are bent backwardly parallel to form a loop on each side with the extremities bent inwardly each toward the other, said extremities being located in said journal portions, under tension whereby the bail member will be normally retained in the plane of the base with the loop members above the same to form a holder for belt attachment.

10. A device of the character set forth, the combination of a frame, a pair of journal members at remote portions on the frame, in which the apertures extend toward each other, said apertures lying in

ties being located in said journal portions, under tension whereby the bail member will be normally retained in the plane of the base with the loop members above the same to form a holder for belt attachment and means on the base for removably holding a watch or similar article.

10. A device of the character set forth, the combination of a frame, a pair of apertured journal members on the frame, and which apertures are each slightly inclined to the base plane, and a holder member in the form of a bail member of single piece of spring wire in which the end portions 15 are bent backwardly parallel to form a loop on each side with the extremities bent inwardly each toward the other, said extremities being located in said journal portions, under tension whereby the bail member will 20 be normally retained in the plane of the base with the loop members above the same to form a holder for belt attachment and the bail member will also be held in a position perpendicular to the base.
25. 11. A device of the character set forth comprising a frame provided with a pair of journal members, and a holder in the

form of a bail member of spring wire provided with loop portions, the extremities of the wire being deflected and inserted in said journal members, respectively, said engaging journal portions being arranged to normally retain the bail lying against the frame to permit the bail to be swung up from the frame and which movement will maintain 30 tension on the loop tending to return the loop to the frame.

12. A device of the character set forth comprising a frame provided with a pair of journal members having the axes out of 35 alinement and a holder in the form of a bail member of spring wire provided with loop portions, the extremities of the wire being deflected inwardly toward each other and inserted in said journal members respectively, said journal portions being arranged to normally retain the bail lying against the frame to permit the bail to be 40 swung up from the frame and which movement will maintain tension on the loop tending to return the loop to the frame.

Signed at New York city, N. Y., this 24th day of May, 1922.

TIMOTHY B. POWERS.
